The Description reported in this Letters Patent and making part of the claim
containing a description in the words of the said Letters Patent, to the
Invention in the Single Iron Frame-Box.

To all whom these presents shall come Be it known that it is the
will of the County of Etowah in the State of Kentucky have in existence a
true and useful Improvement in the single Sled. It is the will and that the following
be a full and exact description thereof. The frame which receives the box to stand
is made in the following form and dimensions the side to receive the upright
post must be eight inches long 8 by 4 inches square with the upright post
8 1/4 inches long 8 by 4 inches square set in the side by two, back to one foot apart
in the clear with a crook back to receive the box 2 1/2 pms. the side the post to have
a groove cut the back 16 inches wide and one inch deep. To receive the gate
in frame while the knife is fixed upon the gate ^{the} 1/2 1/2 inches wide from
end to end the inches thick. The knife is fixed on with 2 iron bolts to be taken off
in order to sharpen the same the spring or iron of which is to be set in the
gate to receive the straw to be cut the base is to be put on with a crook
of 2 1/2 inches deep in an iron in the outside frame and connected to the
gate while the knife is on with a bolt passing through the gate in the 1/2
wide to be three feet long. The box 8 1/4 inches long 8 inches wide
16 inches wide with a crook piece in the back to keep the straw from
passing above the knife. The steel is to be placed in the bottom of the mouth
of box for the knife to work against the knife to be placed on in a slope
of four inches from square. The machine is to be made with the hands
The shop or guide to regulate the length

The ship or guide to regulate the time
of draw to be out is you run with four seconds for the first part of draw &
the last part of draw not exceeding two minutes.

That! Classic as my own invention and not necessarily racism
lengthen the same
